UNITED STATES PATENT OFFICE.

AMBROSE PORTER GAINES, OF SOUTH PITTSBURG, TENNESSEE.

FURNACE-TWYER.

SPECIFICATION forming part of Letters Patent No. 594,786, dated November 30, 1897.

Application filed March 10, 1897. Serial No. 626,847. (No model.)

To all whom it may concern:

Be it known that I, AMBROSE PORTER GAINES, a citizen of the United States, residing at South Pittsburg, in the county of Marion and State of Tennessee, have invented certain new and useful Improvements in Furnace-Twyers for Blast-Furnaces, Cupolas, &c., as fully set forth in the following specification and as shown on accompanying drawings.

10 The object of my invention is to obtain a more effective distribution of the blast than is possible with the usual form of twyers with a round discharge opening or nozzle or with an elongated opening of uniform width. This
15 object is obtained by the use of a twyer provided with a horizontally-elongated blast-orifice or nozzle wider at one or more points or portions than in other points or portions, the effect being that the blast is delivered in
20 the form of a thin film or sheet of varying thickness instead of a round stream or column, as delivered from a round nozzle. A spreading or side-blast effect is also obtained by a peculiar design of the twyer-lip, as herein-after noted and as shown in the accompanying drawings, in which—

Figure 1 is a horizontal section of twyer with blast-pipe in position, with my invention applied thereto and having a round shank adapted to a round or conical cooler. Fig. 2 is a vertical section of the same. Fig. 3 is a face or end view of the same. Fig. 4 is a horizontal section of twyer blast-pipe and cooler in position, said twyer having fan-lipped elongated nozzle and rectangular shank adapted to rectangular cooler. Fig. 5 is a vertical section of the same. Fig. 6 is a face or end view of the same. Fig. 7 is a horizontal section of a blast-furnace through
40 the twyer-line with twyers in position, showing the superficial blast area tributary to each twyer. Fig. 8 is a half side view and half vertical section of twyer with vertically enlarged orifice at center and sides. Fig. 9 is a half-front and half-diagram of same. Fig. 45 10 is a plane projection of twyer designed to deliver a uniform volume of blast to all points in the furnace area tributary to its action.

A is the blast-pipe; F, the cooler; G, the
50 furnace-shell, and B the twyer.

The blast is forced through the round or cylindrical blast-pipe A into the twyer B,

whose blast-orifice C is vertically contracted and horizontally elongated, the effect being that the blast is delivered over a greater horizontal plane than is possible with the same amount of air delivered through a round nozzle of equal capacity.

The direction of the blast-discharge is governed by the form or outline of the nozzle-lips. The strength and volume of blast at any point may also be varied in the same manner and by vertical enlargement or contraction of the nozzle-orifice either at the sides or in the center of nozzle d, or both.

The outer edges of nozzle-lips are approximately equidistant from the axis or center of the column of air delivered by the round blast-pipe, as shown in Figs. 1 and 4. As air under pressure will blow in the direction of the shortest route to less pressure, it is evident that by the use of the fan-shaped nozzle d an equal amount of air is delivered at right angles to the outer edge of this lip at all points of this fan-shaped nozzle, provided the vertical opening between the nozzle-lips d be uniform, and the blast will be horizontally and radially divergent, as shown by light straight lines, Figs. 1 and 4. Now if a larger volume of air at the sides is desired the effect can be accomplished by flaring or vertically enlarging the blast-orifice at the sides and vertically contracting the blast-orifice in the center, Figs. 3 and 6, or vice versa, should greater volume of blast be desired in center of twyer. A stronger center blast can also be obtained by cutting back or shortening the center of the twyer-nozzle in a vertical plane, thus shortening the distance from the axis of the blast-pipe to the lip at this point.

Any desired variation of force or volume of blast at any point may be obtained by varying the proportion of twyer-nozzle area to hearth area at any point, or the twyer-nozzle area may be made uniformly proportionate at all points as follows: The superficial area of the hearth, Fig. 7, is divided into as many fields as there are twyers in the furnace, the boundary being a radial line midway between adjacent twyers. Each of these fields is tributary to its own twyer. The periphery of the nozzle is divided in a longitudinal direction by vertical lines, Figs.

8 and 9. Transferring these lines to the plan view Fig. 7 they become points through which lines are drawn radial to the neutral axis of the blast and at right angles to the periphery 5 of the nozzle-lips and extended to their intersection with the outline of the field tributary to that twyer. The space (1 2, &c.) inclosed between any two of these lines inside of a given field is the exact hearth area tributary 10 to that part of the nozzle-orifice included between these two straight lines. Hence by proportion the hearth area 1, Fig. 7, is to nozzle area 1, Figs. 8 and 9, as the total hearth area Z is to the desired ratio of the 15 hearth area to nozzle area. Thus if the desired ratio of hearth area to nozzle area is fifty to one and the area of the field 2, Fig. 7, is two hundred square inches, the nozzle area 2, Figs. 8 and 9, would be 50:1::200:4, four 20 (4) inches. In the same way all other parts of the nozzle-opening may be definitely proportioned to meet the requirements for any ratio of hearth area to nozzle area.

I have found that by the use of a nozzle 25 vertically contracted in the center and flaring at the sides the blast along the sides of the furnace in some instances proved too strong, while the center-flared nozzle, with little or no flare at the sides of the orifice, as 30 shown in Figs. 9 and 10, gives the best results in furnaces of the form shown. Thus we have a combination in the center flare and the side flare; but it is evident that in 35 furnaces of different design and requirements this fan-shaped elongated type of nozzle may be further varied in the form or proportion of its opening at any point to meet the different requirements.

If a uniform volume of blast at sides and 40 center is desired, an orifice made in accordance with the plan shown in Fig. 10 will meet the requirements. It is evident, however, that if the nozzle-orifice were extended or widened no vertical enlargement at sides

would be necessary, also evident that if the 45 opening were brought nearer the center the vertical enlargement at the sides would have to be correspondingly increased to compensate for the dead-blast area along the walls of the furnace. If, again, a disproportionately large 50 volume of blast should be desired either at the sides, at the center, or at any intermediate point, all that is necessary is to increase the vertical measurement of that particular point or points or restrict at adjacent points. 55

I have found that the form of nozzle-opening in which the central portion is widened or flared is the preferable construction in practice; but it is to be understood that my invention is not limited to this or any other 60 form, as it is only necessary that the widened and narrowed portions of the orifice be symmetrically disposed with reference to the central point of the opening.

I am aware that a twyer-nozzle having its 65 lips shaped substantially on the arc of a circle with elongated orifice is old, and I do not claim such a construction; but

I do claim as my invention—

1. The combination with the blast-pipe, of 70 a furnace-twyer having nozzle-lips conforming approximately to an arc of a circle and forming a horizontally-elongated blast-orifice, said orifice having widened and narrowed portions symmetrically disposed with respect 75 to the central point of the orifice, substantially as and for the purpose set forth.

2. The combination with the blast-pipe, of a furnace-twyer having nozzle-lips conforming approximately to an arc of a circle and 80 forming a horizontally-elongated blast-orifice, said orifice being vertically enlarged at the center, substantially as and for the purpose set forth.

AMBROSE PORTER GAINES.
